UNITED STATES PATENT OFFICE

2,096,198

GLOW PLUG

Hector Rabezzana, Flint, Mich., assignor to General Motors Corporation, Detroit, Mich., a corporation of Delaware

Application October 5, 1936, Serial No. 103,977

5 Claims. (Cl. 123—145)

My invention relates to incandescent igniting devices designed to ignite the combustible mixture in Diesel and similar internal combustion engines at starting, and for a short time after the engine begins to operate; such devices being commonly referred to as "glow plugs" and being characterized by the fact that they include a heating element of high resistance which is heated to incandescence by a current of electricity of low voltage, ordinarily six volts or less.

The object of my invention is to improve and simplify and reduce the cost of such glow plugs, while at the same time enhancing their efficiency for the use for which they are required; to which end my invention contemplates a glow plug wherein the customary outer shell or casing for the insulating member thereof is made unnecessary, and is dispensed with, as well also as a glow plug having improved and more efficient means for connecting the current supply conductors to the plug.

With the above and other objects of invention in view my invention consists in the improved glow plug illustrated in the accompanying drawing and hereinafter described and claimed, and in such variations and modifications thereof, within the scope of the concluding claims, as will be obvious to those skilled in the art to which my invention relates.

30 In the drawing accompanying and forming a part of this specification and wherein the preferred form of my invention is illustrated:

Figure 1 is a view showing a section thereof upon a longitudinally extending central plane, of a glow plug made in accordance with my invention.

Figure 2 is a view showing the current supply connecting means of my improved glow plug in plan, as seen from a position above the same.

40 Figure 3 is a view similar to Figure 2 but showing the current supply connecting means in side elevation.

In the drawing, the numeral 4 designates a portion of the wall of the cylinder of an internal combustion engine, the head thereof in the more usual practice, and which wall has a passage 5 leading into the interior of the cylinder and within which my improved glow plug is received and housed. The plug itself comprises an insulating member 6 made of porcelain or like ceramic material, or of mica, or in fact of any suitable insulating material, the same being enlarged at its central portion and having lower and upper shoulders 7 and 8 the first resting 55 upon a ledge 9 provided within the passage 5,

and the second being provided for holding the insulating member within said passage by a gland nut 10 which is in threaded engagement with the upper end of said passage. Suitable gaskets 11, 12 are provided between the lower shoulder 7 and the ledge 9, and between the upper shoulder 8 and the inner end of the gland nut 10, in order to prevent leakage of gases from within the engine cylinder past the insulating member as will be understood.

The numerals 13, 14 designate electrodes extending through passages in the insulating member and through which current is supplied to a coil 15 of high resistance metal and whereby the latter is heated to incandescence, the coil 15 being within the engine cylinder so that the mixture to be ignited comes into contact therewith. The electrodes are insulated from one another by the material of the insulating member and the interstices between them and the passages through which they extend are filled by suitable cementations or equivalent material 15, 16. These electrodes are made of a good conducting metal, such as copper, and have enlarged heads 17, 18 housed within recesses provided in the lower end of the insulator 6; and their upper ends are upset, as at 19, 20, to hold them within the passages provided for them and permanently assembled with the insulating member. The ends of the igniting coil 15 are welded, brazed or otherwise fastened to the heads 17, 18 as will be understood.

Supported above the upper end of the insulating member 6 is a head 21 made of moulded insulating material such, for example, as bakelite, the same having a depending part or skirt 22 which fits closely about the upper end of the insulating member but is not ordinarily permanently fastened thereto; and the numerals 23, 24 designate internally threaded tubular inserts about which the material of the head is moulded, and whereby they are permanently associated with the head. The numerals 25, 26 designate metallic clamps having projections 27, 28 secured to their lower ends by being riveted thereto, and which projections extend through holes in the depending skirt and the insulating member and into engagement with the electrodes 13, 14, as shown, thereby providing a conducting path between the clamps and the electrodes and at the same time holding the head 21 in place upon the upper end of the insulating member 6.

The numerals 29, 30 designate curved abutments, made commonly of metal, the same being secured to the upper end of the head 21 by

being moulded therein; and 31, 32 are bus bars or equivalent conductors through which current is supplied to the electrodes 13, 14 through the clamps 25, 26 and the projections 27, 28, 5 these conductors being clamped between the upper ends of the clamps and the abutments 29, 30. The clamping action of the clamps is produced by screws 33, 34 extending through holes therein and the inner ends of which are in threaded engagement with the internally threaded inserts 23, 24; and the upper ends of said clamps are bifurcated so as to provide two branches 35, 35, whereby three-point contacts are provided by the branches at the upper ends 10 of the clamps which bear against the bus bars 31, 32 and the projections 27, 28 at their lower ends which engage the electrodes 13, 14.

Having thus described and explained my invention I claim and desire to secure by Letters 20 Patent:

1. A glow plug comprising an insulating member; two electrodes extending through passages in said insulating member and whereby current is supplied to an igniting element at the inner 25 end thereof; a head formed from insulating material, and which head is supported upon the outer end of said insulating member; two metallic clamping members supported upon opposite sides of said head and having projections 30 at their lower ends which engage said electrodes, and the upper ends of which members engage two current supply conductors and clamp them against said head; and screw mechanism between the ends of said clamping members for 35 drawing them toward said head.

2. A glow plug comprising an insulating member having an enlarged central part, and shoulders at the ends of said central part whereby said member may be secured in place within a 40 passage in a cylinder wall; two electrodes extending through passages in said insulating member and whereby current is supplied to an igniting element at the inner end thereof; a head formed of insulating material, and which head is supported upon the outer end of said insulating member; and means for clamping two current supply conductors against opposite sides of 45 said head and for establishing a conducting path between said supply conductors and said electrodes.

50 3. A glow plug comprising an insulating mem-

ber having an enlarged central part, and shoulders at the ends of said central part whereby said member may be secured in place within a passage in a cylinder wall; two electrodes extending through passages in said insulating member and whereby current is supplied to an igniting element at the inner end thereof; a head formed of insulating material, and which head is supported upon the outer end of said insulating member; and means carried by said head 10 for securing two current supply conductors to said electrodes.

4. A glow plug comprising an insulating member; two electrodes extending through passages in said insulating member and whereby current is supplied to an igniting element at the inner 15 end thereof; a head formed from insulating material, and which head has a depending skirt at its lower end which surrounds the outer end of said insulating member; two metallic clamping 20 members supported upon opposite sides of said head and each of which has a projection at its lower end which extends through a hole in said skirt and into engagement with one of the electrodes aforesaid, and the upper ends of which 25 clamping members engage two current supply conductors and clamp them against said head; and two screws, one associated with each of said clamping members, and which screws act to draw 30 said clamping members toward said head.

5. A glow plug comprising an insulating member; two electrodes extending through passages in said insulating member and whereby current is supplied to an igniting element at the inner 35 end thereof; a head formed from moulded insulating material, and which head has a depending skirt at its lower end which surrounds the outer end of said insulating member; two metallic clamping members supported upon opposite sides of said head and each of which has a projection 40 at its lower end which extends through a hole in said skirt and into engagement with one of the electrodes aforesaid, and the upper ends of which 45 clamping members engage two current supply conductors and clamp them against said head; and two screws, one associated with each of said clamping members, and the inner ends of which are in threaded engagement with internally threaded sleeves embedded in said head.

HECTOR RABEZZANA.
